UNITED STATES PATENT OFFICE

CHARLES H. ROLLASON, OF WHEELING, WEST VIRGINIA, ASSIGNOR TO WHEELING STEEL CORPORATION, OF WHEELING, WEST VIRGINIA, A CORPORATION OF DELAWARE

SHEET-METAL CONTAINER

Application filed November 13, 1928. Serial No. 319,096.

This invention relates broadly to sheet metal drums or containers, and more specifically to a cap or closure for the filler spouts of such containers.

5 The primary object of the invention is to provide a cap-like threaded closure for the spouts of sheet metal drums adapted for use as containers for liquids, said closure having associated therewith means whereby chance retracting rotation thereof is prevented, thereby to guard against leakage 10 of the liquid contents.

In describing the invention in detail, reference is herein had to the accompanying drawings, in which—

15 Figure 1 is a head end elevation of a sheet metal drum equipped with my invention;

Fig. 2 is an enlarged fragmentary view of the same; and—

20 Fig. 3 is a sectional elevation on line 3—3, Fig. 2.

Referring to said drawings, 1 designates the head of a container of an ordinary sheet metal drum construction, said head having 25 the usual upturned rim 2 seamed or otherwise attached to the container body.

Located within a depression or countersink 3 provided in the head 1 adjacent to the rim 2 is a vertical neck 4 through which 30 liquid contents are introduced and removed. Said neck is provided with external screw threads for the reception of a cap-like threaded closure 5, and attached in fixed relation to the top of said closure, as by spot welding, shown at 6, is a circular disk 7 having its outer circumferential portion shaped to form an upstanding roll or bead 8.

Provided at suitable intervals in said roll or bead are numerous pairs of perforations 40 9 and 10, the perforations of each pair being located on opposite side of said bead and separated by narrow webs 11.

A flat sheet metal tongue 12 is permanently attached, as by spot welding, shown at 45 13, to the head of the container at a point

adjacent to the countersink 3, and has an eye or perforation 14 provided therein.

The threaded cap or closure 5 is threaded on the neck 4 in air-tight sealing relation thereto, following which a length of flexible wire 15 is passed through the eye 14 of the tongue and through the adjacent pair of perforations 9 and 10 of the disk; then, the opposite end portions are brought together and are tightly attached, as by twisting one on the other. Such attachment of the cap or closure to the stationary tongue serves to maintain the former against chance rearward rotation and thus guards against leakage which would result from a slight re- 55

tracting movement.

Following bringing together of the ends of the wire 15, a lead seal may be applied to said ends for guarding against unauthorized tampering with the contents of the 60 container.

What is claimed is—

1. The combination with the sheet metal head of a container having an opening defined by a threaded neck, of a threaded cap-like closure for screwing upon said neck, and a disk rigidly carried by said closure, said disk having a circumferential upstanding bead provided with perforations adapted for the reception of securing means. 70

2. The combination with the head of a container having a threaded sheet metal neck through which access is had to the contents of the container, of a threaded cap for mounting on said neck, and a disk-like member fixed to said cap and having therein a circumferential upstanding bead provided with circumferentially arranged pairs of radially related perforations adapted for the reception of means whereby it is attached to said head for preventing rotation of said cap. 85

3. The combination with the sheet metal head of a container having an opening defined by a threaded neck, of a threaded 90

cap-like closure of cylindrical flangeless form adapted for assuming threaded relation to said neck, and a disk of less diameter than said closure rigidly mounted upon 5 the top of the latter, said disk having an elevated circumferential portion provided with perforations any of which may afford means whereby said disk may be attached to said head for preventing reverse rotary 10 movement of said closure.

In testimony whereof, I affix my signature.

CHARLES H. ROLLASON.
